UNITED STATES PATENT OFFICE.

FRANK L. CONE, OF WINDSOR, VERMONT.

SPINDLE-BEARING.

1,319,923.

Specification of Letters Patent.

Patented Oct. 28, 1919.

Application filed February 9, 1918. Serial No. 216,329.

To all whom it may concern:

Be it known that I, FRANK L. CONE, a citizen of the United States, residing at Windsor, in the county of Windsor and 5 State of Vermont, have invented new and useful Improvements in Spindle-Bearings, of which the following is a specification.

This invention has relation to automatic screw machines, and more particularly to 10 the turret and work-carrying spindles which are mounted to rotate therein; and it has for its object to provide certain improvements in the construction and arrangement of the spindles and their bearings, and to the arrangement and location thereof in respect 15 of the turret and the bearing in which the turret is mounted to have an intermittent or step-by-step rotation.

Figure 1 of the drawings, which illustrate 20 one embodiment of the invention, represents a longitudinal section (on a plane indicated by the dotted line 1—1, Fig. 3) through the turret and shows one spindle in section and another in side elevation. For simplicity 25 of illustration, one of the spindles which would be seen is omitted in this figure.

Fig. 2 shows in perspective the casting which constitutes the turret.

Fig. 3 represents a section on the line 3—3 30 of Fig. 2.

Fig. 4 illustrates one of the taper bushings.

Fig. 5 illustrates one of the clamps.

The instrumentality embodying the present 35 invention may constitute a component part of an automatic screw machine which is completely illustrated and described in my Letters Patent No. 1,271,540, dated July 9, 1918, to which reference may be had for a description of the bed and the turret bearing 40 in which the turret is journaled, and of the mechanism by which the turret is indexed and locked, since such features constitute no essential part of the present invention.

45 The turret, which is illustrated in detail in Fig. 2, is of the barrel type and is mounted to rotate upon a horizontal axis in bearing frames which are rigidly fixed to the bed of the machine. The turret consists of two end 50 disks 5, 6, which are integral with a plurality of longitudinal bars 7, 7, which are sector-shaped, as shown in Fig. 3. Extending axially outwardly from the end disks there are two diametrically reduced journals 55 8, 9, the former being cylindrical and the latter being tapered or frusto-conical;

and projecting inwardly from said disks there are the peripheral flanges 10 and 11. At 12, 13, there are indicated two solid or fixed frames in which the turret is mounted 60 to rotate. Preferably, the frame 12, while rigidly bolted upon the bed of the machine, is capable of removal therefrom to permit the withdrawal of the turret rearwardly and axially from the frame 13, the latter being, 65 preferably, a solid heavy casting. The peripheral portions of the end disks 5 and 6 and the sector-shaped longitudinal bars 7 project radially for some distance beyond the reduced ends 8 and 9, and overlap the inner 70 walls of the frames 12 and 13. The two end disks are apertured to provide bearings for the reception of four work spindles, of which but two are shown (for the sake of simplicity) and are indicated at 14, 14. 75 These apertures, which are indicated at 15, flare inwardly; that is, they taper in opposite directions toward the end faces of the turret, there being annular flanges 16 which extend inwardly from the end disks 5 and 6 80 and constitute prolongations or extensions of the bearings. Introduced into each of the frusto-conical bearings or apertures thus formed, there is a tapered bushing 17 of suitable material. Each bushing is tapered, 85 with circumferential flanges 18 and longitudinal ribs 19 so as to provide a space for lubricant within the bearing. Each bushing is split longitudinally between the ribs 19, and the flanges are notched, so that the bearing 90 may be easily contracted about its axis. Said bushing is adjustable longitudinally to compensate for wear. For this purpose, the larger end of each bushing projects inwardly beyond the bearing (including the 95 extension flange 16) and is provided with an externally threaded flange 20, with which is engaged internal threads on the outer end of a sleeve 21, said sleeve being either rectangular in cross-section or provided with 100 lugs or projections 22 to facilitate its rotation. Each sleeve is provided with a circumferential rib or flange 23 with which may be engaged a clamp 24 secured by bolts or screws, not shown, to the adjacent end 105 of the turret. These clamps may be segmental in form and they hold the sleeves tightly against the ends of the spindle bearings while permitting said sleeves to be rotated to adjust the bushings longitudinally. Each 110 bushing is held against rotation by a pin 25 passed through an associated annular ex-

tension flange 16 of the spindle bearing and having its end engaged with a slot 27 formed in one of the ribs 18 of the bushing, as shown in section in Fig. 1. By virtue of 5 the construction as thus described, it is apparent that, by rotating a sleeve 21, the associated bushing may be adjusted outwardly to compensate for wear, the bushing being easily contracted as it is forced far- 10 ther into the frusto-conical aperture in which it is located.

Each of the spindles consists of a tube or hollow bar, which, except for the head 28, is cylindrical from end to end, without 15 shoulders, so that it may be inserted endwise into the bushings in which it is journaled. The spindle is held against longitudinal rearward thrusts by two washers 30, 31, interposed between the head and the forward 20 end face of the turret, one of these washers 31 being secured to the head by the pin 32, and the other to the turret by the pin 33. Each spindle is held against longitudinal 25 movement in the other direction by a gear 34 which is secured thereto by a pin 35, said gear bearing against the end of the associated sleeve 21, located in the rear of the front disk, through the medium of a washer 36. At the head ends of the spindles, the 30 sleeves 21 have plane ends, whereas the sleeves, which are connected to the other end of the turret, have bonnets 37 with a rotatable and sliding fit on the spindle to prevent access of dust or foreign material to the 35 threads of the sleeve and the bushing. To prevent any end play of the spindle, abutment screws 38 are passed through the gear 34 in a direction parallel with its axis and having their ends in engagement with the 40 washers 36 bearing against the plane ends of the sleeves 21. After adjustment, each screw may be locked in place by a lock nut 39. Through the front end of the turret, there is passed a sleeve or bushing 40 coaxial 45 with the turret, and having a circumferential flange 41 abutting against the front face of the turret. This bushing is held against rotation by a pin 42 lying in a groove 43. Within the bushing is journaled a shaft section 50 44, which at its front end is so formed as to be capable of being coupled to another driving shaft section. On its opposite end there is pinned to the shaft section 44 a gear 45 which meshes with all four gears 34, so 55 as to rotate the spindles in synchronism and in the same direction. While the spindle and the parts that are carried thereby are shown in section, it is unnecessary to describe these parts in detail as they are well known, except to state that the stock-feeding sleeve is indicated at 50 and the chuck-operating sleeve is indicated at 51.

From the foregoing description it will be seen that each spindle may be easily re- 60 moved from its bearing by removing the pin 65

35 which secures the gear 34 thereto, and that, with the removal of the spindle, the gear 34 becomes detached. Then, upon removing the bolts by which the clamp 24 is secured, the associated bushing may be easily withdrawn from the spindle bearing for replacement or repair. Without removing the spindle, each bushing may be adjusted, ample space being afforded for access thereto between the sector-shaped longitudinal bars 75 7 of the turret. The spindle itself is firmly held against axial movement in either direction, the adjustment of the screws 38 causing the whole spindle to be moved endwise until it is firmly held with its head in engagement 80 with the collar 31. I consider the provision of the inwardly projecting annular extensions 16 of the turret bearings as advantageous for the reason that I am thereby enabled to secure a relatively long support 85 for the bushing and a long bearing for the spindle.

One of the advantages incident to the construction which I have illustrated is that the bushings for the front and rear turret bearings taper outwardly in opposite directions, and are located so as to be accessible between the ends of the turret; and a further advantage is that the means for adjusting the bushings, including the threaded sleeves 21 95 and the clamps 24, are located between the ends of the turret where they are non-obtrusive and yet are easily accessible through the spaces between the longitudinal bars of the turret. The bushings are adjustable 100 without in any manner affecting the adjustment of the spindles, which is a decided advantage,—especially as no end thrust is exerted upon the bushings by the spindles, the bushings serving to resist lateral thrusts 105 only. The main body portion of the turret is much larger in diameter than the bearings therefor, and, by providing the spaced longitudinal bars 7, 7, relatively large gears for driving the spindles may be employed. The 110 turret is therefore light in weight but without sacrificing any support for the spindles or the bushings.

It will be understood, of course, that the spindle-bearing bushings may be provided 115 with apertures for conveying oil from the lubricant-space to the spindle, and that suitable conduits for conducting lubricant through the body of the turret to said lubricant spaces are provided.

Having thus explained the nature of my said invention and described a way of making and using the same, although without attempting to set forth all of the forms in which it may be made or all of the modes 125 of its use, what I claim is:—

1. The combination with bearing frames, of a turret having spaced ends journaled in said frames, oppositely and outwardly tapered bushings fitting complementary aper- 130

- tures in said ends and having cylindrical bores, and spindles having cylindrical portions journaled in said bushings.
2. The combination with a turret having spaced ends, said ends being provided with frusto-conical apertures tapering toward the outer end faces of the turret, of complementally tapered bushings located in said apertures and having cylindrical bores, cylindrical spindles journaled in said bushings, and means located between said turret ends for adjusting said bushings axially.
3. The combination of a turret comprising spaced disks having oppositely and outwardly tapering bearings with inwardly projecting annular extensions or flanges, tapered bushings having cylindrical bores located in said bearings and held against rotation therein, and spindles journaled in said bushings.
4. The combination with a turret comprising end disks, longitudinal spaced bars connecting the said disks, said disks having apertures between said bars which taper toward the outer end faces of said disks, and inwardly projecting annular flanges encircling said apertures, of oppositely tapered bushings located in said apertures, and spindles journaled in said bushings.
5. The combination of a turret having spaced end disks provided with apertures tapering toward the outer faces of said disks, oppositely tapered bushings located in said apertures and held against rotation therein.
- 35 rotatable threaded sleeves located between the end disks and respectively bearing thereagainst and in threaded engagement with said bushings to effect the longitudinal adjustment thereof when said sleeves are rotated independently of the spindles herein mentioned, means for holding said sleeves against axial movement, and spindles journaled in said bushings.
6. The combination of spaced bearing frames; a turret comprising spaced end disks 45 and parallel longitudinal bars connecting peripheral portions of said disks, each disk having an outwardly-projecting diametrically-reduced journal located in said frame; work spindles located within alined apertures in said end disks and projecting beyond said bearing frames, and tapered bushings for the spindles located in complemental apertures each in said end disks, the bushings carried by each disk tapering toward the outer end face thereof.
7. The combination with a turret having end disks and spaced frusto-conical spindle-receiving apertures therein, of work spindles and bushings, in said apertures and in which said spindles are journaled, each bushing having circumferential notched taper flanges and each being longitudinally split.
8. The combination with a turret having end disks provided with tapering spaced spindle-receiving apertures, taper bushings located in said apertures, a sleeve having a threaded engagement with the larger end of each bushing and abutting against one of the end disks, a clamp engaging said sleeve, and with said disk holding said sleeve against axial movement while permitting it to rotate, and means for securing said clamp to said end disk.
9. The combination with a turret having end disks, of a spindle passing through said disks and having a head supported against rearward axial movement by the front end disk, a gear fixed on said spindle in the rear 80 of said disk, and one or more screws passed through said gears exerting their end thrust against said disk, whereby said spindle is held against movement in either direction axially.
- In testimony whereof I have affixed my signature.

FRANK L. CONE.
